(57) **CLAIM**

The ornamental design for a light fixture, as shown and described.

DESCRIPTION

FIG. 1 is a perspective view from below of a light fixture in accordance with my design;

FIG. 2 is a top plan view of the light fixture in accordance with my design;

FIG. 3 is a bottom plan view of the light fixture in accordance with my design;

FIG. 4 is a front elevation view of the light fixture in accordance with my design; and,

FIG. 5 is a side elevation view of the light fixture in accordance with my design, the opposite side being a mirror image of that shown.

The broken lines showing environmental structure are for illustrative purposes only and form no part of the claimed invention.
